ELECTRIC PRESSING IRON

William M. Cissell, St. Matthews, near
Louisville, Ky.

Application March 13, 1941, Serial No. 383,091

9 Claims. (Cl. 38—77)

My invention relates to improvements in an electric pressing iron, and particularly to the type adapted to discharge steam upon material during pressing.

Many improvements have been made in the construction of such pressing irons, some of which embrace generating the steam within the iron, while others embrace means for controlling the humidity or moisture content of steam supplied to the iron from a remote source.

My earlier United States Letters Patent Number 1,799,281, issued April 7, 1931, and entitled "Flatiron" and my co-pending United States application Serial Number 176,000 filed November 23, 1937, now Patent No. 2,241,945, and entitled "Laundry pressing iron" have reference to improvements in the construction of irons of the latter designated type.

My present invention also has particular reference to further improvements in the construction of electric pressing irons that have means for controlling the humidity or moisture content of steam supplied to the iron from a remote source before the same is discharged from the iron onto the material being pressed.

Accordingly, my present invention has for its principal object the provision of an improved relationship for the instrumentalities associated with the steam conduits within the pressing iron.

Another object of my invention is to provide an improved condensation or moisture trap in the steam conduit within the iron.

A further object of my invention is to provide a moisture trap comprising a metallic cup filled with absorbing material of low heat conductivity, preferably asbestos wool, upon which the live steam is discharged within the iron.

A further object of my invention is to provide a super-heating chamber adjacent the heating element in the sole plate, within which the moisture trap is disposed for providing an effective conversion of the untreated steam and all free moisture into a uniform steam having the required humidity.

Another object of my invention is to provide instrumentalities for treating steam supplied to the iron that are simple in construction and easily replaceable.

The advantages of these and other objects will manifest themselves as the following description is read in connection with the accompanying drawing, in which

Figure 1 is a side elevational view of my pressing iron shown partially in section along line 1—1 of Figure 2 for illustrating the construction

and relation of the parts comprising the moisture trap; and

Figure 2 is a plan view of my pressing iron shown partially in section along line 2—2 of Figure 1 for further illustrating the construction and relation of the parts comprising the moisture trap.

In the preferred embodiment of my invention illustrated in the accompanying drawing, the 10 numeral 1 designates a conventional hollow shell or cover 12. The numeral 13 designates a conventional handle having a suitable grip, which handle is secured to and spaced from the sole plate 1 and shell 12 by means of vertical supports 14 and 15.

It is to be understood that the sole plate 1 of my pressing iron is heated by means of a suitable electric heating element 20. Generally, the heating element 20 comprises a conventional triangular shaped heating element disposed in a suitable channel 19 formed in the top face of the sole plate 1 and within the shell 12. In the physical embodiment of the invention the heating element 20 substantially follows the marginal contour of the sole plate 1, and is arranged so that a portion of the heating element is in the sole plate above the chamber containing the moisture trap.

Accordingly, it is to be understood that the 30 steam conduit 10, which enters at the rear of the iron and near the base of the shell 12, extends along the top face of the sole plate and substantially adjacent the electric heating element 20, as illustrated in dotted lines in Figures 1 and 2. 35 Near the forward end of the sole plate, the conduit 10 is arched upwardly so as to extend over the electric heating element and operatively connect a conduit 9, which conduit communicates with the central portion of a circular chamber 40 18.

Therefore, steam from a remote source enters conduit 10 at 11 and is directed into the chamber 18 via conduit 9. Obviously, the untreated steam entering the conduit 10 at 11 is superheated within the conduit 10 by reason of its proximity to the electric heating element 20.

However, by reason of the comparatively short and unrestricted flow of the untreated steam within conduit 10, it is possible for free moisture 50 or globules of water conveyed with the steam to remain in a liquid state. Therefore, I have provided a moisture trap onto which the steam is discharged before the same is discharged from the iron.

55 With reference to Figures 1 and 2, it will be

observed that the numeral 2 designates an annular cup removably secured in the chamber 18 by means of suitable threads. As illustrated in Figure 1, the lower portion of the cup 2 is provided with annular rows of perforations 3, and the outer face of the cup is adapted to form a smooth and continuous surface with the pressing face of the sole plate 1.

Within the annular cup 2 a suitable moisture trap is provided. In the preferred embodiment, the moisture trap comprises a thin sheet metal cup 5 filled with asbestos wool 7 and covered by a cupped guard 8 preferably made of wire mesh. In this respect it is particularly important to observe that the central portion of the mesh guard beneath conduit 9 is open to provide unrestricted communication for the steam discharged from the conduit 9 with the asbestos wool of the moisture trap. It is also important to observe that the lower face of the sheet metal cup 5 is provided with a series of offset portions 6 for spacing the lower face of cup 5 from the perforated face of cup 2. Similarly, with reference to Figure 2, it will be observed that a series of vertical grooves 16 are formed in the vertical walls of the annular cup 2, which grooves communicate with the space between the lower face of cup 5 and the perforated face of cup 2, and with the chamber 18.

Accordingly, it will be apparent that the steam discharged upon the moisture trap enters the same through the central opening in the wire mesh guard, whereupon the steam passes through the asbestos wool and escapes through the wire mesh guard, and, via grooves 16 and the space between the faces of cups 2 and 5, the steam is discharged from the chamber 18 via grooves 16 and perforations 3.

It will be apparent that all free moisture or globules of water are removed from the steam as it is discharged onto the moisture trap, and as the steam passes upwardly through the asbestos wool.

Obviously, by reason of the proximity of the heating element 28 to the moisture trap, all captured moisture and water globules are converted into dry steam which dry steam rises and mixes with the dry steam discharged from the chamber 18.

With further reference to Figure 2, it will be observed that I have also provided three additional chambers 17 within the sole plate 1, which chambers communicate with the annular chamber 18. To provide for the discharge of steam from the chambers 17, the sole plate 1 is provided with perforations 4 communicating with the respective chambers.

Therefore, having thus described my invention, I claim:

1. The combination with a steam-dispensing pressing-iron having a steam chamber in the body thereof, and having perforations in the pressing face thereof communicating with the said chamber; means operatively associated with the said chamber for delivering steam thereto; and a steam distributor and condensation trap within the said chamber disposed between the said steam delivery means and the said perforations for separating water of condensation from the steam delivered into the said chamber, the said distributor and trap comprising a metallic cup filled with absorbing material of low heat conductivity and having a wire mesh extending over the said absorbing material, for retaining the same in the said cup.

2. In a steam-dispensing pressing-iron; a sole plate having a recess therein extending upwardly from the pressing face of the same; a first cup removably secured in the said recess and having the bottom wall thereof perforated and disposed within the said recess so that the outer surface of the perforated bottom-wall forms a continuation of the pressing surface of the said sole plate; a second cup disposed within the said first cup and having a solid bottom-wall spaced upwardly from the perforated bottom-wall of the first cup to provide a steam distribution chamber between the solid bottom-wall of the second cup and the perforated bottom-wall of the first cup, the said second cup having the upper end of the side wall thereof spaced downwardly from the upper surface of the said recess to provide a steam receiving chamber between upper surface of the said recess and the upper end of the said second cup; a conduit operatively communicating with the upper surface of the said recess, for delivering steam and water of condensation into the said second cup; an absorbing material of low heat conductivity disposed within the said second cup, for separating the water of condensation from the steam delivered therein; a wire mesh disposed within the said receiving chamber and extending over the said absorbing material, for retaining the same in the said second cup; and conduit means operatively communicating with each of the said chambers for conducting treated steam from the receiving chamber into the said distribution chamber, thereby to discharge the treated steam into the perforations in the bottom wall of the said first cup and onto the surface of material being pressed by the said iron.

3. In a steam-dispensing pressing-iron; a sole plate having a recess therein extending upwardly from the pressing face of the same; a first cup removably secured in the said recess and having the outer surface of the bottom wall thereof forming a continuation of the pressing surface of the said sole plate; a second cup disposed within the said first cup and having the bottom wall thereof spaced upwardly from the bottom wall of the first cup, the said second cup also having the upper end of the side wall thereof spaced downwardly from the upper surface of the said recess, thereby to provide chambers above and below the said second cup; a moisture separator of low heat conductivity disposed within the said second cup, for separating water of condensation from steam discharged thereupon; a steam conduit operatively communicating with the chamber above the said second cup, for conducting steam into the said chamber and discharging the same upon the moisture separator within the said second cup; conduit means, operatively associated with each of the said chambers, for conducting steam from the chamber above the said second cup into the chamber below the said second cup; and conduit means operatively associated with the chamber below the said second cup, for discharging the steam received therein onto the surface of material being pressed by the said iron.

4. A steam-dispensing pressing-iron as defined in the preceding claim including a heating element operatively associated with each of the said chambers, and the moisture separator within the said second cup, for superheating the steam received therein, and for vaporizing the water of condensation collected by the moisture separator.

5. In a steam-dispensing pressing-iron; a sole

plate having a chamber formed in the forward end of the body thereof; a retaining cup disposed within the said chamber and dividing the same into a steam receiving chamber above the said retaining cup and a steam distribution chamber below the said cup; a moisture separator of low heat conductivity in the said retaining cup for separating water of condensation from steam discharged thereupon; a steam conduit communicating with the said receiving chamber for conducting steam from a remote source and discharging the same onto the said moisture separator; conduit means operatively associated with the said receiving and distribution chambers for conducting steam from the receiving chamber into the said distribution chamber; and means operatively associated with the said distribution chamber for discharging the steam received therein onto the surface of material being pressed by the said iron.

6. In a steam-dispensing pressing-iron; a sole plate having a chamber formed in the forward end of the body thereof and substantially adjacent the pressing surface of the said sole plate; a baffle disposed horizontally within the said chamber and dividing the same into a steam receiving chamber above the said baffle, and a steam distribution chamber below the said baffle; a moisture separator of low heat conductivity disposed within the receiving chamber and supported upon the said baffle for separating water of condensation from steam discharged thereupon; a steam conduit communicating with the receiving chamber above the said moisture separator for conducting steam from a remote source and discharging the same upon the said moisture separator; conduit means operatively associated with the receiving chamber above the said moisture separator and the said distribution chamber, for conducting steam from the said receiving chamber into the said distribution chamber; means operatively associated with the said distribution chamber for discharging the steam received therein onto the surface of material being pressed by the said iron; a wire mesh disposed within the said receiving chamber and extending over the said moisture separator; and a heating element operatively associated with the chamber and the said wire mesh, for superheating steam received within the said chambers, and for vaporizing water of condensation separated from the steam by the said moisture separator.

7. In a steam-dispensing pressing-iron; a sole plate having a chamber formed in the forward end of the body thereof and substantially adjacent the pressing face thereof; a plate disposed horizontally within the chamber and dividing the same into a steam receiving chamber above the plate, and a steam distribution chamber below the said plate; a moisture separator of low heat conductivity disposed within the said receiving chamber and supported upon the said plate for separating water of condensation from steam discharged thereupon; a steam conduit communicating with the receiving chamber above the said moisture separator for conducting steam from a remote source and discharging the same onto the moisture separator; a plurality of conducting channels disposed about the marginal edges of the said plate and operatively communicating with the receiving chamber above the

said moisture separator and the said distribution chamber, for conducting steam from the receiving chamber into the said distribution chamber; the pressing face of the said sole plate having a plurality of perforations therein operatively communicating with the said distribution chamber, for discharging the steam received therein onto the surface of material being pressed by the said iron; a wire mesh disposed within the said receiving chamber and extending over the said moisture separator; and a heating element operatively associated with the chambers and the said wire mesh, for super-heating steam received within the said chambers, and for vaporizing water of condensation separated from the steam by the said moisture separator.

8. In a steam-dispensing pressing-iron; a sole plate having a chamber formed in the forward end of the body thereof; a shallow metallic cup disposed horizontally within the said chamber and dividing the same into a steam receiving chamber above the said cup, and a steam distribution chamber below the said cup; a moisture separator of low heat conductivity in the said cup for separating water of condensation from steam discharged thereupon; a wire mesh covering extending over the said moisture separator and adapted to retain the same in the said cup; a steam conduit communicating with the said receiving chamber above the said moisture separator for conducting steam from a remote source and discharging the same upon the said moisture separator; and a plurality of steam conducting channels disposed about the marginal edges of the said cup and operatively communicating with the receiving chamber above the said cup and the said distribution chamber, for conducting steam from the receiving chamber into the said distribution chamber; the pressing face of the said sole plate having a plurality of perforations therein operatively communicating with the said distribution chamber, for discharging steam received therein upon the surface of material being pressed by the said iron.

45 9. A steam-dispensing pressing-iron; a sole plate having a chamber formed in the body thereof; a baffle disposed horizontally within the said chamber and dividing the same into a steam receiving chamber above the said baffle, and a steam distribution chamber below the said baffle; a moisture separator of low heat conductivity disposed within the receiving chamber and supported upon the said baffle, for separating water of condensation from steam discharged thereupon; a wire mesh disposed within the said receiving chamber and extending over the said moisture separator, for retaining the said separator upon the said baffle; a steam conduit operatively associated with the said receiving chamber for conducting steam into the said receiving chamber and discharging the same upon the said separator; conduit means operatively associated with the said receiving and distribution chambers, for conducting steam from the receiving chamber into the said distribution chamber; and conduit means operatively associated with the said distribution chamber, for discharging the steam received therein onto the surface of material being pressed by the said iron.
